UNITED STATES PATENT OFFICE.

PAUL C. NOWATSKE, OF MUKWONAGO, WISCONSIN.

PUMP-OPERATING MECHANISM.

1,077,290.

Specification of Letter's Patent.

Patented Nov. 4, 1913.

Application filed October 31, 1912. Serial No. 728,926.

To all whom it may concern:

Be it known that I, PAUL C. NOWATSKE, a citizen of the United States, residing at Mukwonago, in the county of Waukesha, 5 State of Wisconsin, have invented certain new and useful Improvements in Pump-Operating Mechanism; and I do hereby declare the following to be a full, clear, and exact description of the invention, such as will 10 enable others skilled in the art to which it appertains to make and use the same.

This invention has relation to novel and useful improvements in pumps and more particularly to an improved drive mechanism 15 therefor.

The primary object of the invention is evolved in the provision of a drive mechanism in which the piston has connection with a vertically movable rack while a pinion or gear is rotatably driven to engage 20 and reciprocate the rack whereby a longer stroke may be imparted to the pump piston with comparatively little or less power than is required by an ordinary crank or eccentric operated pump.

Another object of the invention is to provide a rotatable drive shaft adapted for lateral sliding movement whereby a pinion carried on its inner end will continuously move 30 around a novel form of rack member so as to convert a rotary motion of the drive shaft, driven from any suitable source, into a vertical reciprocating motion of the pump rod or piston.

With the above and other objects in view, the invention consists of certain combinations and arrangements of parts as will be hereinafter more fully described, claimed and illustrated in the accompanying drawings, in which:

Figure 1 is a front elevation of a pump having my improved drive mechanism connected thereto. Fig. 2 is a central vertical sectional view taken on the line 2—2 of Fig. 1. Fig. 3 is a top plan view of the device. Fig. 4 is a horizontal sectional view taken on the line 4—4 of Fig. 1. Fig. 5 is a horizontal sectional view taken on the line 5—5 of Fig. 1. Fig. 6 is a detail sectional view showing one of the teeth of the rack bar.

In illustrating the practical embodiment of the invention there is shown the upper portion or head of a pump 10 having the usual piston, not shown, working therein and connected to the piston rod 11 to which it

is desired to transmit reciprocable movement. For this purpose and in order to avoid the great disadvantages caused by the use of the ordinary crank disk or eccentric 60 commonly used in pumps, whereby the power necessary for operating the same is considerably increased and the stroke of the piston shortened, I provide a casting embodying a supporting head 12 which is secured to the 65 pump cylinder 10 by set screws 13.

Formed integral with the supporting head 12 is an upright 14 carrying at its upper end a horizontally disposed guide frame 15 of open form and which overhangs the pump 70 as illustrated. These parts are formed as a single casting together with opposed side braces 16 which rigidly support the guide frame for receiving the working parts and sustaining the jars incident to its operation 75 in working the pump.

Detachably connected to the upper end of the piston rod by means of a set screw 17 is the cross head 18 which is vertically movable in the guide frame and formed with 80 opposite tongues 19 movably engaged between the rear portion of the frame and guide blocks 20 carried by and coacting with the latter to form guideways for receiving the cross head. The forward portion of the 85 guide frame 15 is horizontally slotted to receive a sliding bearing 21 which rotatably supports a horizontal drive shaft 22 in turn carrying on its inner end a pinion or gear 23.

A rack bar 24 is secured to the forward face 90 of the cross head and is formed of a plurality of rollers 25 having beveled heads 26 and each roller is rotatably supported on a bolt 27, the head of which prevents displacement of the rollers in each instance. The 95 drive shaft is rotatably supported outwardly of the slotted portion of the frame in an enlarged bearing 28 carried at the upper end of a stationary arm 29 secured at its lower end to the supporting head and has a 100 knuckle joint 22' to permit transverse movement of the pinion in its travel around the rack bar so as to vertically reciprocate the latter and piston connected thereto. A

power driven pulley 30 is loosely mounted 105 on the drive shaft and is operable through the medium of a drive belt engaged by a shifter element 31 operable by means of a lever 32 while a tight pulley 33 is secured to the shaft and capable of operation by means 110 of a hand crank 34.

In the operation of the device the shaft is

rotated by either of the means above described and by continuously rotating the pinion, the latter is caused to travel around the rack bar and impart vertical reciprocable movement to the latter to correspondingly move the piston of the pump. Thus, it will be seen that the length of the rack bar may be increased so that the length of the stroke may be comparatively indefinitely increased whereby a greater amount of lifting force either in water or air pumps is accomplished with the same amount of power.

It will be observed that the knuckle or universal joint 22' is located inwardly of the shaft bearing 38 to permit swinging of the inner end of the shaft, the bearing being held rigid by side braces 35 branching from the casting or frame 15. The inner or threaded ends of the bolts 27 are also reduced in size where disposed through the crosshead 19 to provide a shoulder 36 limiting the inward displacement of the bolts and preventing the rollers from binding on the upright.

I claim:

1. In a pump, the combination with its cylinder and piston rod; of a supporting head mounted on the cylinder, a horizontal guide frame supported above the head, a rack bar detachably connected to the piston rod and vertically movable in the frame, a

transversely shiftable drive shaft carried by the frame in mesh with the rack bar and means for rotating the shaft to reciprocate the rack bar and piston rod connected thereto. 35

2. The combination with a pump having a reciprocable piston and the pump rod; of a supporting head mounted on the pump, set screws operating through said head to secure the same to the pump, a casting formed integral with the head and comprising a rear upright, a horizontal frame at the upper end of the upright and braced to the sides of the head, said frame having a horizontally slotted forward portion, a rack bar comprising 45 a plurality of spaced rollers, a cross head attached to the pump rod and supporting said rollers, said cross head being vertically slidable in the frame, a shaft having a pinion at its inner end in mesh with the rack bar, an arm braced to the head and rotatably supporting the shaft, a sliding bearing engaged in the slotted portion of the frame and rotatably receiving the shaft for transverse movement and means for rotating the 55 shaft.

In testimony whereof, I affix my signature, in presence of two witnesses.

PAUL C. NOWATSKE.
